UNITED STATES PATENT OFFICE.

JAMES A. PLOPPER, OF CHICAGO, ILLINOIS, ASSIGNOR, BY MESNE ASSIGNMENTS, TO INTERNATIONAL HARVESTER COMPANY, OF CHICAGO, ILLINOIS, A CORPORATION OF NEW JERSEY.

BINDING MECHANISM.

SPECIFICATION forming part of ~~the~~ Patent No. 784,702, dated March 14, 1905.

Application filed September 28, 1901. Serial No. 76,958.

To all whom it may concern:

Be it known that I, JAMES A. PLOPPER, a citizen of the United States, residing at Chicago, in the county of Cook and State of Illinois, have 5 invented certain new and useful Improvements in Binding Mechanisms for Grain-Harvesters, of which the following is a specification.

My invention relates to certain new and useful improvements in binding mechanisms for 10 grain-harvesters, and is designed to produce a device of the class described that shall be simple in its construction and efficient in its operation and that shall be especially adapted for use in corn-harvesters, although it will be 15 understood that it can be used in connection with any other kind of harvesting-machine that may be desired.

Figure 1 is a front elevation of the mechanism embodying my invention, showing how it is 20 mounted for longitudinal adjustment. Fig. 2 is an end elevation of the same, on a somewhat larger scale, in section on the line A A of Fig. 1. Fig. 3 is an end elevation of the other end on the same scale as Fig. 2. Fig. 4 is a sectional view through the chain-tightener. Fig. 25 5 is a rear elevation of the supporting-arm for the chain-tightener. Fig. 6 is a rear elevation of a portion of the mechanisms on a still larger scale; and Fig. 7 is an enlarged view of 30 a portion of the mechanism shown in Fig. 2, showing in full and dotted lines the compressor - hook in the three positions it assumes—while the gavel is being formed, when the bundle is tripped, and when the bundle is 35 discharged.

The U-shaped binder-frame 10 has secured thereto beneath and parallel to the lower horizontal sleeve 11 the rod 12, which has its right-hand end 13 secured to the lug 14, projecting 40 downwardly from said sleeve, while its left-hand end is secured in the casing 15, bolted to the sleeve 11 beneath the vertical portion 16 of the frame. The rod 12 rests on an antifriction-roller 17, carried by a short standard 45 18, secured upon the transverse sill 19, connected to the longitudinal binder-support sill 20 by the interposed bolster 21. Another rolling-support for the frame 10 is furnished

by the arm 22, secured to and projecting downwardly from the right-hand end of the 50 sleeve 11 and having the antifriction-roller 23 journaled at the lower end thereof in position to roll upon the horizontal portion of the angle-iron sill 20. To prevent the binder-frame from being moved vertically relative to the 55 main frame, I provide a hook 24 on the top of the standard 18, taking over a rod 12, and likewise an inwardly-turned lug or flange 25 on the end of the arm 22, which projects beneath the horizontal portion of the sill 20. A 60 brace 26 for the arm 22 is conveniently secured thereto and to the lug 14. To provide for the driving of the packer-shaft 27, while permitting the longitudinal movement of the binder, I square a portion 28 of said shaft, 65 which slides through a correspondingly-shaped aperture in the hub of a sprocket-wheel 29, to which power is applied and which is journaled in a suitable bearing formed in the bracket 30, secured to the transverse sill 70 31, which is connected to the binder-support sill by the bolster 32. It will be noticed that this longitudinal adjustment of the binder serves to bring the two supports together in 75 binding short grain and to separate them in binding long grain, so that short grain is bound nearer the butts than long grain. This effect is caused by the fact that the butt-adjuster is stationary with reference to the frame, and consequently the movement of the 80 binder longitudinally of the frame necessarily varies the distance from the butts at which the bundle is tied. It will also be noticed that the two points of support of the binder are brought closer together when short grain is 85 being tied and are directly beneath the grain, thus concentrating the weight of the grain on the binder over the points of support—an advantageous construction, inasmuch as it maintains the equilibrium of the grain over the 90 points of support. Vice versa, when the binder is moved backward for long grain the points of support are separated and still maintained beneath the grain, the weight of which is always evenly distributed above the points 95 of support, an advantage not found in the or-

dinary construction, where the points of support are always the same distance apart irrespective of the length of the grain, which cannot be located directly above the points of support in all adjustments.

The packer-shaft 27 is journaled at its right-hand end in a preferably self-adjusting bearing 33, mounted in an arm projecting downwardly from a bracket 34, secured to the framework on the under side of the deck 35, which is shown only in Figs. 2 and 7 and omitted in the other figures. This bracket 34 is secured to the angle-iron strip 36, which is secured to one or more lugs 44, projecting forward from the sleeve 11, and which in turn has secured thereto a bracket 37, which has an arm 38, projecting forwardly therefrom and terminated by the bearing-sleeve 39, in which is mounted the upper end of the packer-arm link 40, which has the lower end of the packer-arm 41 pivoted thereto upon the packer-crank 42 at 43 in the customary manner. The bracket 47, which, together with the bracket 37, supports the deck 35, is secured to the strip 36 near its inner end. This bracket 47, which is similar to the bracket 37, has the arm 48 secured thereto, terminating in the bearing-sleeve 49 for a packer-arm link 50, which has the other arm, 51, pivoted to the lower end thereof, this packer-arm being vibrated by the packer-crank 52, to which it is pivoted at 53, the two cranks 42 and 52 being connected by the sleeve 54. Just beyond the packer-crank 52 the shaft 27 is supported by the preferably self-adjusting bearing 55, mounted in the bracket 56, (see Fig. 6,) secured to and projecting downwardly from the right-hand end of the sleeve 11. It is also supported near its left-hand end by the preferably self-adjusting bearing-sleeve 57, secured in the lower end of the bracket 15.

Rigidly secured upon the left-hand end of the packer-shaft 27 is the cross-head 58, constituting the constantly-rotating half of the 45 intermittent clutch mechanism for driving the cam-shaft when the bundles are to be bound. Loosely mounted on the shaft 27 between the cross-head 58 and the bearing 57 is the sleeve 59, constituting the intermittently-rotating 50 half of the clutch mechanism. This sleeve has the ears 60 thereon, between which is pivotally secured by a pin 61 the driving-dog 62, which has the enlarged end 63 thereof normally contacting with the end 64 of the trip-stop 65 and held thereby against the resistance of the spring 66, secured to the lug 67 on the opposite side of the sleeve 59 and to the lower end of the dog 62 in such position that the clutch-lug 68 on the outside thereof 55 is out of the path of the clutch-roller 69, journaled on the inside of the cross-head 58. When the trip-stop 65 is shifted by the mechanism to be subsequently described, the spring 66 throws the driving-dog 62 into the position 60 shown in dotted lines in Fig. 3, where the

clutch-lug 68 is engaged by one of the rollers 69 and the sleeve 59 is compelled to rotate with the packer-shaft 27 until it is released therefrom by the means to be described.

Arranged to rotate with and preferably formed integral on the inner end of the sleeve 59 is the gear-pinion 70, which meshes with a corresponding pinion 71, journaled on the bearing-stud 72, projecting outwardly from the bracket 15. The pinion 71 has secured thereto and preferably formed integral therewith the sprocket-wheel 73, which by means of the chain 74 rotates the cam sprocket-wheel 75 once by several of its own rotations. The cam-wheel 75 is secured to the left-hand end 80 of the cam-shaft 76, which is journaled in the sleeve 77, constituting the upper horizontal arm of the U-shaped binder-frame. The cam-shaft 76 has on its right-hand end the discharge-arms 78 and the knotter-driving gear-wheel 79, which operates the knotter mechanism (not shown) in the customary manner for this class of devices. The breastplate 80 and its associated parts are supported from the end of the sleeve 77 in the customary manner. The cam-wheel 75 has projecting from the outer surface thereof the pintle 81, upon which is pivoted one end of the customary link 82, the other end of which is secured to the crank-arm 83 of the needle rock-shaft 84 at 85 a greater distance from the center of the shaft 84 than its other end is from the center of the cam-shaft 76, so that at each rotation of the cam-wheel 75 the needle rock-shaft 84 is swung forward and back through the necessary arc to operate the needle 85, secured to the end thereof just beyond the end of the sleeve 11, in which it is journaled.

The trip-stop 65 is secured on a short sleeve 86, loosely mounted on the needle-shaft 84 between the crank-arm 83 and the stationary collar 87, projecting from the end of the sleeve 11, concentric therewith and forming a portion of the bearing for the shaft 84. The rod 88, pivoted to the crank arm 83 at 89, as best seen in Fig. 6, passes through an aperture formed in the lug 90 on the trip-stop 65, and a helically-coiled expanding-spring 91, surrounding the rod 88 and interposed between the upper side of the lug 90 and the nut 92, screwed on the threaded end of the rod 88, serves to hold the trip-stop 65 yieldingly in the position shown in Fig. 6 with the lug 90 against the arm 83 and its end 64 in engagement with the enlargement 63 of the end of the driving-dog 62. The rearward limit of movement of the sleeve 86 is determined by the lug 93 thereon, which overlaps and co-operates with the lug 94, secured on the collar 87. The binder trip-shaft 95, whose crank end 96 normally rests just beneath the trip-stop 65 as it is rocked by the means to be described, serves to swing the stop 65 so that its end 64 is out of engagement with the end 63 of the driving-dog 62, so that the spring 66 can operate to swing 130

the dog 62 into position to engage the clutch members and start the rotation of the cam-shaft 76. When the needle rock-shaft swings back to its normal position after the bundle 5 is bound, the trip-stop 65 is in position to intercept the driving-dog 62 and rock it until the sleeve 59 and the shaft 27 are unclutched; after which the binding mechanism rests until another gavel is formed by the packer-arms 10 and the trip-shaft 95 is rocked again to release them. By adjusting the position of the nut 92 on the rod 88 the tension of the spring 91 will be regulated and the size of the bundle, and more especially the amount of pressure 15 necessary to control the tripping mechanism, will be regulated.

The binder trip-shaft 95 has the U-shaped offset 97 therein between the main body thereof and its eccentric end 96 to avoid interfering with the chain 74, which is also held away from the offset, as seen in Figs. 3 to 5, by a pulley-wheel 98, journaled on the bearing-sleeve 99, formed on the lower end of the arm 100, which has the cam-surfaces 101 on the 20 upper end coöperating with the complementary cam-surfaces 102, formed on the bracket 103, projecting from the vertical portion 16 of the binder-frame 10, the arm 100 being held in the desired position of adjustment by the 25 bolt 104 passing through suitable recesses in the arm and the bracket and having the nut 105 coöperating therewith. The trip-shaft 95, as seen in Fig. 6, is journaled at one end in a recess 106, formed between the bracket 30 35 40 45 50 55 60 65 70 75 80 85 90 95 100 105 110 115 120 125 130 135 140 145 150 155 160 gavel trips the mechanism and starts the binding operation again.

While I have shown my invention as embodied in the form which I at present consider best adapted to carry out its purposes, it will be understood that it is capable of some modifications and that I do not desire to be limited in the interpretation of the following claims by the language thereof, but only as may be necessitated by the state of the prior art.

What I claim as new, and desire to secure by Letters Patent of the United States, is—

1. In a binding mechanism, the combination with the deck having the binder trip-shaft extending longitudinally beneath it, of the compressor-hook, the compressor-hook-supporting arm, connections between said arm and shaft which permit a movement of the arm substantially parallel to the deck to move the shaft, and supports for said compressor-hook-supporting arm so that as it moves in a line parallel to the deck the binder trip-shaft is moved to start the binding mechanism; substantially as described.
2. In a binding mechanism, the combination with the deck having the binder trip-shaft extending longitudinally beneath it, of the compressor-hook, the compressor-hook-supporting arm pivotally connected to said trip-shaft, and supports for the arm which together with said pivotal connection constrain it and the hook to move parallel to the deck to move the trip-shaft to start the binding mechanism and subsequently to swing down to permit the discharge of the bundle; substantially as described.
3. In a binding mechanism, the combination with the deck having the binder trip-shaft extending longitudinally beneath it, of the compressor-hook, the compressor-hook-supporting arm pivotally connected to said trip-shaft, the compressor-hook shaft having a crank-arm thereon, the link pivotally connected at its opposite ends to the compressor-hook-supporting arm and the crank-arm, and means for preventing the rotation of said compressor-hook shaft except when a bundle is to be discharged; substantially as described.
4. In a binding mechanism, the combination with the frame having the sleeve 11, of the deck supported above said sleeve, the binder trip-shaft 95 journaled in the rear of said sleeve and having the crank end 112

above said sleeve 11, the compressor-hook-supporting arm 114 having the U-shaped portion 117 pivotally connected to the end 112 and extending beneath the continuation of the axis of said sleeve 11, the compressor-hook 116 secured on the forward horizontal end of the arm 114, the compressor-hook shaft 124 located beneath the sleeve 11 and having the normally horizontal crank-arm 123, the link 121 connecting the end of the crank-arm 123 and the horizontal portion of the compressor-hook-supporting arm 114, and means for preventing the rotation of the compressor-hook shaft 124 except when a bundle is to be discharged; substantially as described.

5. In a binding mechanism, the combination with the frame having the sleeve 11, of the binder trip-shaft 95 journaled in the rear of said sleeve and having the crank end 112 at one end, the crank end 96 at the other end, the U-shaped bend adjacent to the crank end 96, the trip-stop coöoperating with the crank end 96, and the binding mechanism including the sprocket-wheel 73 and the sprocket cam-wheel 75 connected by the sprocket-chain 74 in the plane of the U-shaped bend in the binder trip-shaft; substantially as described.

6. In a device of the class described, the combination with the framework of the machine, of the binding mechanism longitudinally movable thereon, and connections between said framework and binding mechanism comprising two supports, one carried by the framework and the other by the binding mechanism, and which are brought together as the binder is adjusted for binding short grain and which are separated as the binder is adjusted for binding long grain; substantially as described.

7. In a device of the class described, the combination with the framework carrying the supporting-bracket 18 provided with an antifriction-roller and having the substantially horizontal bar 20, of the binding mechanism longitudinally movable thereon and including the rod 12 resting on the antifriction-roller on the bracket 18, and the downwardly-projecting bracket 22 having the antifriction-roller 23 resting on the bar 20; substantially as and for the purpose described.

JAMES A. PLOPPER.
